UNITED STATES PATENT OFFICE.

JOHN E. WIGHTMAN, OF NEW BRITAIN, CONNECTICUT, ASSIGNOR TO NORTH & JUDD MANUFACTURING COMPANY, OF SAME PLACE.

DESIGN FOR ROLLER-BUCKLES.

SPECIFICATION forming part of Design No. 11,649, dated February 10, 1880.

Application filed August 23, 1879. Term of patent 7 years.

To all whom it may concern:

Be it known that I, JOHN E. WIGHTMAN, of New Britain, in the county of Hartford and State of Connecticut, have originated and produced a new and original Design for a Roller-Buckle, of which the following is a full, clear, and exact description, reference being had to the accompanying drawings, making part of this specification, in which—

10 Figures 1 and 3 are front elevations of a roller-buckle which embody my design. Fig. 2 is a rear elevation of the same, and Fig. 4 is a sectional view of the same on line xx of Fig. 1. The design relates particularly to the side arms, $a a$, of the buckle at each end of the roller b , and has for its object to impart an appearance of extra strength and a plump round form, although in fact said arms are nearly flat. From the ends of the roller b the arms curve 15 outward, and gradually extend into a position substantially transversely to said roller, and then join the body c , to which the tongue is

hinged. These arms, especially at a little distance from the ends of the roller, are flattened and quite thin, the edges standing in an oblique position, as shown by the sectional view in Fig. 4. The outside of said arms is rounded, as shown, while their inside is more nearly flat. The roller, when separately considered, is of the ordinary form. 25

I claim as my invention—

In a buckle, the design for the side arms, a , flattened for the major portion of their length, rounded upon their front ends, set obliquely so as to flare from the front outwardly, curved 30 toward each other at the front end, and having substantially a round form at their junction with the cross-bar, substantially as shown and described. 35

JOHN E. WIGHTMAN.
